UNITED STATES PATENT OFFICE.

JOHN LUKASZEWSKI, OF CHICAGO, ILLINOIS.

FOUNTAIN-BRUSH.

1,349,517.

Specification of Letters Patent. Patented Aug. 10, 1920.

Application filed February 18, 1920. Serial No. 359,512.

To all whom it may concern:

Be it known that I, JOHN LUKASZEWSKI, a citizen of the United States of America, residing at Chicago, in the county of Cook 5 and State of Illinois, have invented certain new and useful Improvements in Fountain-Brushes, of which the following is a specification.

This invention relates to certain new and 10 useful improvements in fountain brushes and has for its primary object the provision of a bulbous handle portion for a brush that is adapted to contain the water or liquid soap that may be delivered to the bristles 15 of the brush when the device is held in an upright position with the bristles downwardly directed.

A further object of the invention is to 20 provide a fountain brush especially designed for shaving purposes wherein there is provided a bulbous handle portion for containing fluid to be delivered to the brush bristles and with supporting feet inclosing the brush handle and constituting a support to hold 25 the brush in upright position when temporarily out of use to prevent the flow of fluid to the brush bristles.

With the above general objects in view and others that will become apparent as 30 the nature of the invention is better understood, the same consists in the novel form, combination and arrangement of parts hereinafter more fully described in connection with the accompanying drawings.

In the drawing wherein like reference characters designate corresponding parts throughout the several views,

Figure 1 is a perspective view of a fountain shaving brush constructed in accordance with the present invention,

Fig. 2 is a vertical cross sectional view of the same, and

Fig. 3 is a fragmentary sectional view of 45 a modified form of the invention showing a manually operated screw plug controlling communication between the bulbous handle portion and the brush bristles.

Referring more in detail to the accompanying drawing, there is provided as shown in Figs. 1 and 2 a shaving brush embodying a back 4 having an annular channel 5 formed in the outer end thereof for the reception of the brush bristles 6 55 which are secured therein in any preferred manner. The brush back 4 is provided with

an inner chamber 7 opening at its inner end at the edge of said back and being internally threaded for the reception of the thimble 8 having an inwardly directed cone-shaped flange 9 upon its inner end with an opening 10 at the apex thereof as shown in Fig. 2. A bulbous handle 11 has the open end thereof frictionally received within the thimble 8 for engagement with the adjacent 65 face of the cone-shaped flange 9.

Supporting legs inclose a bulbous handle 11 and embody a plurality of wire members 12 bent at their inner ends as at 13 to provide supporting feet as illustrated while 70 the outer ends thereof are suitably secured as at 14 in the inner face of the brush back 4 so that the brush may be set in an upright position when the bulbous handle 11 is filled with fluid to prevent the passage of the fluid to the brush bristles 6. As shown in Fig. 2 the wall 15 closing the outer end of the chamber 7 and surrounded by the bristles 6 is provided with a plurality of perforations 16 to permit the passage of fluid from 75 the brush handle to the bristles. With a device of this character, the moisture of the bristles 6 is easily under control of the user as it is only necessary to squeeze the bulbous handle 11 and force the fluid contents thereof through the flange opening 10 and through the openings 16 to the bristles of the brush, thereby controlling the amount of moisture in the brush bristles. During 80 the operation of shaving, the brush may be temporarily set aside when out of use upon the supporting feet 13 which will hold the brush in the upright position illustrated and prevent the flow of fluid contained in the brush handle to the bristles.

A modified form of the invention is shown in Fig. 3 wherein the brush back 4 has an annular channel 5' at its outer end for the reception of the brush bristles 6 and is provided with an internally threaded axial bore 17 for the threaded reception of a thimble 18 extending from one end of the bore to the other end thereof and having a spaced parallel inwardly directed and internally threaded annular flange 19 extending from the outer end thereof and between which flange and thimble the outer open end of the bulbous handle 11' is secured. A screw plug 20 is threaded into the outer end of the threaded flange 19 and provides a 110 closure to prevent the passage of fluid from the bulbous handle 11' to the brush bristles.

6. When it is desired to use the brush disclosed in Fig. 3, the handle 11' is rotated to remove the thimble 18 from the brush back 4' so as to present the screw plug 20 for 5 removal thereof, after which the thimble and handle are replaced in the brush back and the device then operates in a manner as described in connection with Fig. 2.

10 While there are herein shown and described the preferred embodiments of the present invention, it is to be understood that minor changes may be made therein without departing from the spirit and scope of the invention as claimed.

11 What is claimed as new is:—

1. A fountain brush of the type described comprising a back, bristles secured to the

outer end thereof, said back having a passage communicating with said bristles, a 20 bulbous handle detachably connected to the inner end of said back, and supporting legs for holding the brush in upright position carried by the back.

2. A fountain brush of the class described 25 comprising a back, bristles fixed to the outer end of the back, said back having an inner chamber and a passage extending from the chamber to the bristles, a thimble threaded into said chamber, an inwardly directed 30 cone-shaped flange carried by said thimble, and a bulbous handle carried by said thimble.

In testimony whereof I affix my signature.
JOHN LUKASZEWSKI.
